UNITED STATES PATENT OFFICE.

JOHN HENRY NEAVE, OF RAINOW, NEAR MACCLESFIELD, COUNTY OF CHESTER, ENGLAND.

METHOD OF TREATING HATS MADE FROM FELTED MATERIALS.

SPECIFICATION forming part of Letters Patent No. 408,925, dated August 13, 1889.

Application filed October 15, 1888. Serial No. 288,135. (No model.) Patented in England April 25, 1887, No. 5,908; in France December 7, 1887, No. 187,445; in Belgium December 7, 1887, No. 79,832; in Brazil May 9, 1888, No. 576; in Germany May 16, 1888, No. 45,869, and in Italy August 8, 1888, No. 23,890.

To all whom it may concern:

Be it known that I, JOHN HENRY NEAVE, of Rainow, near Macclesfield, in the county of Chester, England, a subject of the Queen of Great Britain, have invented certain new and useful Improvements in the Manufacture of Hats from Felted Materials, (for which invention I have received Letters Patent as follows: in England, No. 5,968, dated April 25, 1887; in France, No. 187,445, dated December 7, 1887; in Belgium, No. 79,832, dated December 7, 1887; in Germany, No. 45,869, dated May 16, 1888; in Italy, No. 23,890, dated August 8, 1888, and in Brazil, dated May 9, 1888, No. 576,) of which the following is a specification.

This invention relates to improvement during manufacture in the method or process of treating hats made from felted materials, and has for its object the consolidating and rendering more cloth-like the texture of the felt, and in rendering permanent a bright and glossy surface upon hats.

In addition to the ordinary and well-known methods of finishing or polishing felt hats, especially by means of hot ironing, such hats are also prepared with a bright glossy polish in two ways: (a) by a long artificial nap on the surface of the cloth, consisting of polished ends of hair or fiber extending beyond the body portion of the material, produced by subjecting the surface of the felt to a rapidly revolving abrasive surface, whereby the ends of the fibers are drawn outward and left upon the surface, as has been fully set forth in the specification of patent issued to me, No. 271,351, January 30, 1883, and (b) by a very short nap, or the absence of nap, the ends of the hair on the surface being polished by a rapidly-revolving smooth polishing-surface or velour applied to the surface of the material in a manner very similar to that described in the specification of the said Patent No. 271,351. A bright glossy polish produced by either of these methods or others that have been tried is readily lost or deteriorated by the action of water or a damp at-

mosphere. I have also found that the texture of the material, after being treated as described in the specification of the said Patent No. 271,351, becomes somewhat loosened or opened.

This invention is designed, primarily, to be applied to hats that have been finished or polished with a bright and glossy polish by either of the methods stated for the purpose of consolidating the texture of the material and rendering the gloss and polish thereon permanent when subjected to the action of damp atmosphere or water.

It consists, essentially, in subjecting the fabric at a certain stage in the process of manufacture to a strong mechanical pressure or compression, and at the same time to the action of a highly-heated fluid—such as steam or water—under pressure.

It is to be noted that I do not claim the application of mechanical pressure, moisture, or heat separately considered, the invention residing in their joint or simultaneous application to the fabric, so that the fibers are held in close and firm contact with each other while the moisture is acting thereon.

It is to be understood that the pressure referred to herein is a pressure so applied that it tends to compress, consolidate, or reduce the thickness of the fabric.

The material will be compressed tightly upon a suitable block, and the heated fluid may penetrate the material from one or both, an equal pressure surrounding it on all sides, or may be forced direct through the material, the pressure being applied on one side of the material only.

The drawings annexed show suitable apparatus designed for carrying out the invention.

Figure 1 is a sectional elevation of block upon which the hats may be tightly compressed before being placed in the bath of water or steam; Fig. 2, a side elevation of apparatus for use when the steam is forced through the hats; Fig. 3, a sectional elevation of Fig. 2; Fig. 4, a plan of Fig. 3; Fig. 5, a plan of perforated

plate C; Fig. 6, a sectional elevation of perforated cap for compressing the hat-bodies instead of the canvas covering and plate C.

In the drawings, A is a perforated block or shape upon which the hats are tightly compressed prior to being subjected to the further treatment of a highly-heated fluid under pressure. The pressure is applied to the hat-bodies preferably by means of a canvas covering B, tightly drawn and pressed down over the hat-bodies by means of the perforated plate C. Instead, however, of canvas B and perforated plate C, a perforated metal block or shape D, Fig. 6, may be used, which will be tightly clamped over the hat-bodies when drawn over the shape A.

In Figs. 2 and 3, E is a steam chamber or chest, over which the perforated block A, which receives the hats, may fit.

G is a large chamber placed below E, supplied with steam from the feed-pipe H. The chamber G communicates with chest E, and is fitted at the top with a baffle-plate g or other contrivance to prevent condensed water being thrown into chest E.

H is the steam-feed pipe.

I is a chamber placed so as to receive any condensed water that may be blown forward from the feed-pipe H and guide it down to the bottom of chamber G, where it escapes by the small pipe J.

K is a pipe to drain condensed water from the chamber E.

The pipes J and K are supplied with stop-taps *j* and *k*.

L are cramps fitted on pivots and supplied with screws to hold the metal plate C or shape D in position and give the required amount of pressure or compression to the hat material.

The metal block A upon which the hats are placed, may be made of any shape required, and, where it is desired that the fluid should act upon the material at one side only, in some instances will not be perforated.

When carrying out the invention the hat or hat-bodies, after being prepared and polished, as hereinbefore described, are drawn down upon the block A, one on top of another, to the number of three or four, and the porous or perforated covering B or D, preferably the canvas one, placed over them and securely fastened, so as to hold and compress the hat material tightly to prevent the moving or curling of the fibers, more particularly of the outer ones, under the influence of the fluid.

When the hats are covered with the canvas, the plate C is placed over them and screwed tightly down by the cramps L. This brings pressure upon the brims and draws the canvas tightly over the crowns and sides of the hats. To avoid the brims being marked by the folds of the canvas, it is desirable frequently to use two of these plates—one to be placed immediately upon the brims of the hats underneath the canvas, while the second is placed upon the top of the canvas, which being drawn into folds by the plate, will

bring the needful pressure upon the crowns of the hats. When the hats are covered with the perforated plate D, it is similarly pressed tightly down over the hat material by the cramps L to give the desired pressure to the material.

Instead of a canvas or metal covering for compressing the hats during the process of treatment, any other suitable textile, porous, or perforated material may be employed that will allow of the passage of steam through it.

In Figs. 2 and 3 is shown the apparatus for use in forcing the steam direct through the material. The block A, with the hat-bodies, is placed in position on the steam-chest E and secured thereto by the cramps L, which also impart the required pressure to the hats. Steam at, say, from five to ten pounds pressure is admitted through the inlet steam-pipe H and chamber G to the chest E. The steam, having no other means of exit, is forced through the perforations in the block A, through the hats, and through the covering of canvas or other material by which they are compressed. It is obvious that the block A may be reversed and placed down into the chest E, the steam passing through the hats from the outside to the inside.

I have not shown the apparatus for use in treating the hats either with steam or water where the pressure is equal on all sides, as any steam-tight or water-tight chamber or vat may be employed for the purpose, and the hats after having been compressed upon the block A, are placed therein. In a steam-chamber a pressure of steam of from five to twenty pounds may be employed, and in a vat while boiling the pressure may be from five to ten pounds. The length or duration of the process in each instance should be from twenty to thirty minutes, or in some cases even less. It is desirable to allow the hats to remain upon the block to cool off for, say, twenty or thirty minutes after they come out of the bath and before removing the mechanical pressure, and this drying will be assisted if the blocks are made of metal of suitable thickness. For the purpose of consolidating and tightening the texture of felt it may be subjected to this process at any stage during the process of manufacture, and, if found desirable, the process may be repeated one or more times before and after the "finishing" of the hats; but for the purpose of rendering the bright and glossy appearance of the hats permanent the process must be employed after the finishing operation, and a considerable independent compressing pressure kept upon the hats while they are subjected to the action of the heated fluid under pressure. By this means any opening of the felt that may have resulted from the finishing process will be closed up and the brightness imparted to the surface rendered permanent.

Hitherto I have obtained the best results by applying this process to hats that have been "finished" or polished by the methods

hereinbefore described. Hats polished by these methods and afterward subjected while under an independent pressure to the action of a highly-heated fluid under pressure will 5 be made to closely resemble highly-finished broadcloth. The somewhat velvety appearance produced by the method described in the specification of my patent, No. 271,357, will be removed by this process, and the 10 closeness and solidity of the texture of the felt increased and the brightness rendered much more permanent. I obtain especially good results by taking hats that have been polished by the method described in my 15 specification of Patent No. 271,357, of 1883, and subjecting them to a hot bath in the manner above described, afterward allowing them to cool off before removing them from the block, then after thorough drying subjecting 20 them to a process of velouring, and afterward hot-pressing in a hydraulic or other hot press. When I desire to obtain a very high polish, I subject the hats to the action of a rapidly-revolving machine-velour; otherwise 25 the velouring may be done by hand in any usual manner. By this method of treating the hats I obtain a hat with a more permanent and more glossy finish and at less expense than can be done by the old system of 30 ironing. I do not, however, limit the invention to hats so prepared or finished, as it may be applied to hats for the purpose of consolidating the fibers of the felt before finishing, or to hats finished by any other process for the 35 purpose of fixing or rendering permanent the finish or polish.

What I claim as my invention, and desire to secure by Letters Patent, is—

1. The process of treating hats during manufacture, which consists in subjecting the hat to the action of a highly-heated fluid under pressure while the hat or hat-body is tightly compressed or subjected to an independent pressure, either for the purpose of consolidating 40 the texture of the material or of fastening the finish or polish, or for both purposes, substantially as described.

2. The process of treating hats during manufacture, which consists in tightly compressing 45 the hat-body on a shape or block and subjecting the hat-body, when so compressed in a chest, chamber, or bath, to the penetrating action of a fluid—such as steam or boiling water—under pressure.

3. The improved method of finishing felt hats with a permanent gloss or brightness, which consists in subjecting the felt surface to the action of a rapidly-revolving abrasive 55 surface, whereby the ends of the fibers are

drawn outward beyond and laid upon the 60 body of the felt, then tightly compressing the hat on a block or shape, and finally subjecting it to the action of a highly-heated fluid (steam or water) under pressure, substantially as described. 65

4. The improved method of finishing felt hats with a permanent gloss or brightness, consisting in first polishing the fibers of the hat by a rapidly-revolving velour or other means, then tightly compressing the hat on 70 a block or shape, and finally subjecting the hat, when so compressed, to the action of a highly-heated fluid (steam or boiling water) under pressure to render the polish permanent. 75

5. The improved method of finishing felt hats with a permanent gloss or brightness, which consists in subjecting the felt surface to the action of a rapidly-revolving abrasive surface, whereby the ends of the fibers are 80 drawn outward beyond and laid upon the body of the felt, tightly compressing the hat on a block or shape, subjecting the hat, when so compressed, to the action of a highly-heated fluid (water or steam) under pressure, and 85 finally polishing with a rapidly-revolving velour, substantially as described.

6. The improved method of finishing felt hats with a permanent gloss or brightness, consisting in first polishing the fibers of the 90 hat by a rapidly-revolving velour or other means, tightly compressing the hat on a block or shape, subjecting the hat, when so compressed, to the action of a highly-heated fluid (steam or water) under pressure, and finally 95 polishing with a rapidly-revolving velour, substantially as described.

7. The process or method of finishing felt hats with a permanent gloss or brightness, which consists in polishing the surface by 100 application to a rapidly-revolving surface, compressing them on a block or shape, subjecting them to a bath of a highly-heated fluid (steam or water) under pressure, allowing them to stand and cool before removing them 105 from the block, thoroughly drying them, velouring them with a rapidly-revolving velour, and finally hot-pressing them in a hydraulic or other hot press, all substantially as described. 110

In testimony whereof I have signed my name to this specification in the presence of two subscribing witnesses.

JOHN HENRY NEAVE.
